DESIGN.

No. 29,069.

G. W. REAM.

PLOWSHARE.

Patented July 19, 1898.

(Application filed June 15, 1898.)

UNITED STATES PATENT OFFICE.

GEORGE W. REAM, OF CANTON, OHIO, ASSIGNOR TO THE BUCHER & GIBBS PLOW COMPANY, OF SAME PLACE.

DESIGN FOR A PLOWSHARE.

SPECIFICATION forming part of Design No. 29,069, dated July 19, 1898.

Application filed June 15, 1898. Serial No. 683,521. Term of patent 14 years.

To all whom it may concern:

Be it known that I, GEORGE W. REAM, a citizen of the United States, residing at Canton, in the county of Stark and State of Ohio, 5 have invented and produced a new and original Design for a Plowshare, of which the following is a specification.

In the accompanying drawings, Figure 1 is a side view of the share, while Fig. 2 is a top view. Fig. 3 is a view of the share from the front.

The leading feature of the design is in the outline of the share and its connected shin-piece, which rises from the share proper. The 15 share has a point A thickened on one edge and tapering to the front and opposite edge, and from this point the line of the share extends at an angle between the points B and C. The surface of the share is inclined from this

edge upwardly to the edge D E, and a shin-piece F extends upwardly in a curved line, forming a continuation of the straight edge of the share, this line extending from the point to the top of the shin-piece. The face of the shin-piece forms a practical continuation of the curved face of the share, and the rear line G E is approximately parallel to the front line of the share-piece. The lower and upper edge of the share proper are connected by a straight line D C. A hole occurs in the 30 share at H, adjacent to the angles E.

What I claim is—

The design for a plowshare as herein shown and described.

GEORGE W. REAM.
